UNITED STATES PATENT OFFICE.

WILLIAM M. BRITTON, OF COLUMBUS, OHIO, ASSIGNOR OF ONE-HALF TO
T. R. CLURE, OF COLUMBUS, OHIO.

INTERNAL-COMBUSTION ENGINE.

SPECIFICATION forming part of Letters Patent No. 748,045, dated December 29, 1903.

Application filed September 4, 1902. Serial No. 122,029. (No model.)

To all whom it may concern:

Be it known that I, WILLIAM M. BRITTON, a citizen of the United States, residing at Columbus, in the county of Franklin and State 5 of Ohio, have invented a certain new and useful Improvement in Internal-Combustion Engines, of which the following is a specification.

My invention relates to the improvement of gasoline-engines or engines of that type ordinarily designated as "internal-combustion" engines; and the objects of my invention are to provide an improved engine construction of this class wherein means are provided for the continuous combustion of the mixed gas 15 and air throughout the stroke of the piston; to provide, in connection with my improved engine, a plurality of power-cylinders and pistons, the latter soarranged and operated as to insure one of the same being in an operative 20 position at all times; to provide improved means for controlling or regulating the air-pressure; to provide improved means whereby a higher air-pressure will be maintained on the gasoline or within the gasoline-reser- 25 voir than within the valve through which the air is fed to the igniting or combustion chamber; to provide improved means for controlling the exhaust; to provide an improved valve-gear mechanism for controlling the supply 30 of mixed gasoline and air to the combustion-chamber, and to produce other improvements the details of which will be more fully pointed out hereinafter. These objects I accomplish in the manner illustrated in the accompanying drawings, in which—

Figure 1 is a plan view of my improved engine. Fig. 2 is a front end view of the same. Fig. 3 is a sectional view on line *x x* of Fig. 1. Fig. 4 is a sectional view on line *y y* of Fig. 1. Fig. 5 is a central vertical section through my improved valve-gear and the feed-valve for the combustion-chamber, said view being taken on line *s s* of Fig. 6. Fig. 6 is a plan view of Fig. 5. Fig. 7 is a 45 sectional view on line *t t* of Fig. 6. Fig. 8 is a detail view in perspective of one of the feed-valves. Fig. 9 is a central sectional view of a portion of the same. Fig. 10 is an end view of the air-compressor cylinder. Fig. 11 is a sectional view on line *q q* of Fig. 10. Fig. 12 is an inner face view of the out-

let-valve of the air-compressor cylinder. Fig. 13 is a view of the opposite side of said valve. Fig. 14 is a side elevation of a pressure-controlling device which I employ in the 55 manner hereinafter described, and Fig. 15 is a sectional view on line *v v* of Fig. 14.

Similar numerals refer to similar parts throughout the several views.

In carrying out my invention I employ a 60 suitable base-frame 1, upon which are mounted three parallel power-cylinders 2. In rear of these power-cylinders upon the base-frame 1 are provided shaft-boxings 3, in which is journaled a crank-shaft 4, the latter having 65 adjacent to one of its ends a crank 5 and at the opposite end a crank 6. At the center of the shaft is carried an intermediate crank 7, said cranks 5, 6, and 7 being so arranged with reference to each other as to project or radiate from the shaft from imaginary lines on the periphery of said shaft, which are approximately one hundred and twenty degrees apart. Carried on one of the outer ends of the crank-shaft is a fly-wheel 8, and connected with the cranks 5, 6, and 7 are the outer 70 ends of piston-rods 9, 10, and 11. These piston-rods extend, respectively, into the cylinders 2, carrying on their forward ends pistons, one of which is shown at 12 in Fig. 3. 75

With the pin of the central crank 7 I also connect the upper bifurcated end of a piston-rod 13, the latter extending downward and forward and pivotally connected with a piston 14, which is adapted to fit and slide with- 80 in a lower inclined air-compressor cylinder 15. With the outer arm 6^a of the crank 6 is connected the upper end of a piston-rod 16, the lower end of which is pivotally connected with a piston 17, which is adapted to fit and 85 slide within a vertical air-pump cylinder 18. This air-pump cylinder is formed in its otherwise closed lower end with inlet and outlet openings which are controlled by valves 19 and 20. The valve 19 has coiled about its 90 downwardly-extending stem portion below the cylinder a spring 21, which serves to normally close said inlet-opening by holding the valve 19 seated therein. The outlet-valve 20 is normally pressed upward and retained 95 seated in the outlet-opening through the medium of a spring 22, which bears between the

under side of said valve and the upper side of the base-plate 18^a of said cylinder. This base-plate forms the bottom of a downward extension of the cylinder 18, and the space 5 between said base-plate and the cylinder-bottom is divided by a central partition 18^b into inlet and outlet compartments 23 and 24, the compartment 23 having an inlet-opening 23^a and the compartment 24 having an outlet-opening, from which leads a pipe 24^a. This pipe 24^a leads to a gasolene-tank 25 and into the upper end thereof. Each of the power-cylinders is formed on its forward end with an outwardly-extending neck or tubular projection 26, (see Fig. 3,) and each of these necks or projections terminates in a vertically-disposed valve-casing, the central one of which I have indicated at 27. (See Figs. 3 and 5.) Within each of these valve-casings 27 is rotatably mounted a hollow valve or cylindrical body 28, the upper end of which is closed and the lower end of which is in communication with a tubular downward extension 27^a of the casing 27. Each of the 25 valve-bodies 28 has its upper end provided with a vertical stem or rod 29, on the upper end of which is carried a bevel-pinion 30. Each of the valves 28 is provided in its upper portion with a wall-opening or port 31, through 30 which communication is adapted to be established between the interior of said valve and the outer end of the corresponding power-cylinder neck 26. (See Fig. 8.) On the periphery of each of the valves 28 and below 35 the opening 31 I form a transverse groove 32, at the center of the length of which is provided an inclined port 33, which communicates with the interior of the valve. With the rear side and lower portion of the valve-casing 27 and each of the valve-casings 27^c and 27^d, which are arranged, respectively, on opposite sides of said valve-casing 27, opposite and in connection with the outer cylinders 2, is formed a rearwardly and down- 40 wardly extending tubular arm 34, which is closed at its lower end and which at its upper end is adapted to communicate with the port 33 of the valve 28. Extending transversely in front of the upper portion of the 45 base-frame is a gasolene-supply pipe 37, the latter having arms 36, which connect, respectively, with the tubular projection 34 of the valve-casings 27, 27^c, and 27^d. The flow of gasolene from these pipe-arms 36 into said 50 tubular projections is regulated by needle-valves 35, which are indicated more clearly in Fig. 2 of the drawings. This gasolene-supply pipe 37 is connected with the lower portion of the interior of the gasolene-tank 25 55 through a pipe 37^a, which is shown more clearly in Fig. 3 of the drawings.

Leading out of the upper portion of the lower and forward end of the air-compressor cylinder 15 is a short tubular valve-casing 38, 60 which communicates with the interior of the cylinder 15 through the medium of a conical valve-opening 39. Within the valve-casing

I provide a valve-body 40, so formed as to be adapted to close the opening 39 from the outer side. This valve 40 is provided at intervals 70 with radially-arranged bearing projections 41, which are adapted to bear against the inner end of the casing 38, about the opening 39 thereof. Into the outer end of the casing 38 is screwed one end of an outlet-pipe 42, and 75 between the latter and the valve 40 is interposed a spring 43, the tendency of which is to hold said valve in its closed position, as shown in Fig. 11. Below the valve-opening 39 I provide in the cylinder end an opening 44, 80 which, in conjunction with the inner end of an outwardly-projecting valve-guide or cage 45, forms a seat for a conical valve-body 46, which when closed against said seat has its inner surface flush with the inner end of the 85 cylinder 15. The valve 46 is provided with a stem 46^a, which has a slideable support in the outwardly-extending cage or guide 45, as shown. On the outer side of said guide the valve-stem is threaded and provided with an 90 adjustable stop-nut 47, between which and the end of the guide is interposed a spring 48. 49 represents a binding-plate through which the valve-stem 46^a passes loosely, the lower end of said binding-plate being hinged at 50 95 to the lower side of the guide projection 45. Supported from and above the cylinder 15 is a cap-like body 51, into the center of the upper side of which leads a pipe 52. Within this cap-like body is provided a horizontal 100 diaphragm 53, which is provided on the under side of its center with a contact projection or lug 54. Pivoted in front of this cap-body is a bell-crank lever 55, the upper arm 55^a of which extends beneath the diaphragm 105 53 and has its upturned end supported adjacent to the diaphragm-lug 54. The downwardly-extending arm 55^b of said lever is curved about the valve-casing 38, as shown more clearly in Fig. 10, and has its lower end 110 contacting with the outer side of the upper end portion of the binding-plate 49. The upper portion of the arm 55^b has passing loosely therethrough an outwardly-projecting pin 56 the outer threaded portion of which 115 carries a nut 57, between which and the lever-arm is interposed a spring 58, this spring serving to normally press the lever-arm 55^b inward and to hold the binding-plate 49 in a vertical or substantially vertical position. 120 The pipe 42, which leads outward from the valve-casing 38, is continued in the form of united pipe-sections outward and upward, its upper end uniting with the downward extension 27^a of the central valve-cylinder 27, 125 within which is contained that valve 28 which regulates the supply of air and gasolene to the chamber formed within the tubular projection 26 of the central power-cylinder 2. Through the medium of a transverse pipe 59, 130 which is indicated more clearly in Fig. 2 of the drawings, the remaining valve-cylinders 27^c and 27^d or the valve-cylinders which belong to the end power-cylinders 2, commun-

cation is established between the pipe 42 and the interiors of the valve 28.

Journalized in front of the upper portion of the forward ends of the cylinders 2 in bracket-arms 60, which project from said cylinders, is a horizontal shaft 61. On this shaft are fixed eccentric or cam bodies 62, one for each of the power-cylinders. Each of these cam-bodies is connected, through the medium of a coiled spring 63, (see Fig. 5,) with one end or face of a bevel gear-wheel 64, which is loosely mounted on said shaft 61, said spring being coiled loosely about the shaft. In constructing each of these gear-wheels 64 I form the same with a rearwardly-extending portion 64^a, which terminates in an enlarged or wheel-like head 64^b. This head 64^b is in the nature of a segmental gear-wheel and has formed thereon a limited number of gear-teeth, such as are indicated at 65 in Fig. 7. I also affix to the shaft 61 adjacent to each of the heads or gear-segments 64^b the inner end of an arm 66, said arm having its outer enlarged end portion pivotally connected, through the medium of a bolt 67, with one of the apexes of the cam-frame 68, this cam-frame, while having curved outer sides, presenting somewhat the outline of a triangle and having on the upper side of its base portion near its inner and wider end a limited number of successively-arranged gear-teeth 69, which are adapted to gear with the teeth 65 of the bevel-gear extension-head 64^b. Each of the cam-frames thus formed is inclosed within a casing, such as is indicated at 70, through which casing the shaft 61 passes loosely. The inner side or surface of this casing opposite the frame 68 is in the form of a spiral curve which extends from one side of the casing to a point 70^a, from which it is continued in the arc of a circle to a point 70^b, this latter point being connected at 70^c with the point of beginning of said spiral curve through the medium of a short outward curve 70^d. Each of the bevel gear-wheels 64, as indicated in Figs. 3 and 5, gears with one of the horizontal bevel-pinions 30, which are carried, as heretofore described, upon the valve-stems 29. The shaft 61 carries adjacent to one end a bevel gear-wheel 61^a, which gears with a bevel gear-wheel 61^b at right angles therewith and carried on the forward end of a rearwardly-extending shaft 61^c. This shaft 61^c carries on its rear end a bevel gear-wheel 61^d, which gears with a similar wheel 61^e on the crank-shaft 4.

The pipe 52, which leads from the chamber formed by the cap 51 of the air-compressor cylinder, as indicated in Fig. 3 of the drawings, leads into the pipe 42, from which a pipe 60 leads rearward to an air-reservoir 72. This pipe 71 is provided, as indicated in Fig. 2 of the drawings, with a valve 73. Above the pipe 71 the pipe 42 is provided with a valve 74, which controls the passage of air upward through said pipe 42 and its branch arms 59. The pipe 42 has leading therefrom to the pipe 24^a a pipe 75.

In the construction of each of the power-cylinders 2 I form in the upper side thereof, near its inner or forward end, an exhaust-opening 76, into which is screwed one end of an angular exhaust-pipe 77, having its outer end open and its lower end, which enters the opening 76, shaped to form a seat for a valve 78, which is carried on the lower end of a vertical stem or rod 79, which passes upward through a stuffing-box in the upper side of the exhaust-pipe, said stem carrying between said stuffing-box and its enlarged head a spring 80, which normally holds said valve 78 in a closed position.

Fulcrumed from a standard 81, which rises from the forward end of each of the power-cylinders 2, is a valve-operating lever 82. (See Figs. 1, 2, and 3.) Each of these levers has its rear end portion in contact with the head of one of the valve-stems 79 and has pivoted within its bifurcated forward end a friction-roller 83. Each of these friction-rollers is in contact with the periphery of one of the cam or eccentric bodies 62 of the shaft 61. Extending upward from each of the power-cylinders 2 is a bracket 84, and in said brackets is journalized a transverse shaft 85. Connected with this shaft and rising therefrom one above each of the power-cylinders is an arm 84^a, and with the upper ends of these arms are connected forwardly-extending bars 87, the forward ends of which are respectively connected with upwardly-projecting lugs 88 of the valve-gear casings 70. As indicated in Fig. 3 of the drawings, one of the arms 84^a is extended upwardly to form an operating lever or handle.

As indicated in Figs. 3, 14, and 15 of the drawings, the pipe 75 is intersected by a pressure-controlling case 89, which is separated into two compartments by a central diaphragm 90, the latter having a comparatively small central opening 91. That section of the pipe 75 which leads from the pipe 24^a connects with the casing 89 through an opening 90^a on the rear side of said casing, while that section of the pipe which leads from the casing to the pipe 42 connects with said casing through an opening 90^b on the forward side thereof. The center of one of the side plates of the casing 89 is formed with an outwardly-extending boss 89^a, through the central threaded opening of which passes a screw 92, the pointed inner end of the latter entering the central opening 91 of the diaphragm and normally closing said opening. The opposing plate or side of the casing 89 is also provided with a boss-like projection 89^b, into which passes a screw 93, the inner end of which within an enlargement of the interior of said boss bears against the outer end of a spring 94, the inner end of which bears against the diaphragm 90.

Leading into each of the chambers formed by the tubular extensions 26 of the power-cylinders are wires 95 and 96, these wires, which are shown in Fig. 3 of the drawings,

leading to a suitable source of electricity and current-controlling apparatus.

In order to illustrate the operation of my improved engine, we will assume that the valves 73, 74, and 35 are closed and that the air above the gasoline in the tank 25 and within the air-reservoir 72 is under pressure. This initial pressure may be imparted by any suitable means, such as the employment of a hand-pump. The valves above mentioned being opened, air from the reservoir is passed through the pipe 71, thence into the pipe 42, and through the latter and the pipe 59 to the interior of the valves 28. The gasoline which is under pressure in the tank 25 will pass upward through the pipe 37, thence through the pipe-arm 37^a and the pipe 37 to the tubular arms 34, from which the gasoline will be discharged into the valves 28 when the grooves 32 of said valves register with the openings at the upper ends of said tubular arms 34. Assuming that one of the valves 28 has its opening 31 in communication with one of the combustion-chambers 26 formed by the outwardly-projecting tubular extension of one of the power-cylinders 2, as shown in Fig. 3, and, further, assuming that the piston of the power-cylinder mentioned is in the inner end portion thereof, it will be understood that the combined gasoline and air will pass from the interior of the valve into said combustion-chamber and that an electric spark produced by closing a circuit through the wires 95 and 96 will result in igniting said mixture of gasoline and air and through the expansion of the products of combustion thus created the piston will be moved toward the outer end of the cylinder. The supply of mixed gasoline and air thus provided is sufficient to insure a continuous burning of the same throughout said outward movement of the piston, my invention thus distinguishing from that class of gas or gasoline engines in which the piston is operated by the results of an explosion or the substantially instantaneous burning of the mixture. The relative arrangement of the crank-carrying piston-rods insures one of said pistons being in position at all times to be acted upon by the products of combustion, as above described. Rotary motion is imparted to the valves 28 through the medium of the gear-wheels 64 and 30 and shaft 61, said shaft receiving its rotary movement from the shaft 61^c, which in turn is driven through the medium of the gears 61^b and 61^c from the crank-shaft, said crank-shaft receiving its motion from the reciprocation of the piston-rods of the power-cylinders. The relative positions of the valves 28 insure said valves having their openings 31 successively in communication with the combustion-chambers 26 of the power-cylinders.

The manner of contributing motion from the shaft 61 to the stems of the valves is as follows: The rotation of said shaft 61 and the consequent rotation of the cam-body 62 re-

sults, through the spring connection 63 with the bevel gear-wheel 64, in imparting tension to said spring and rotation to said wheel 64, 70 and through the gearing of the latter with one of the bevel gear-wheels 30 a corresponding rotation is imparted to the valve-stem. The motion thus imparted to said valve-stem is, however, varied, as hereinafter described. 75 The rotation of the shaft 61 results in each of the arms 66 being carried about said shaft and in a like movement of the corresponding cam-frame 68. This cam-frame being thus carried in the direction of the arrows shown in 80 Fig. 7 has its point in contact with the spiral plane or surface of the interior of the casing 70 while traveling between the points 70^c and 70^a, and owing to the fact that the distance between the point of said cam-frame and the 85 center of the shaft 61 accordingly decreases in the above-described movement it will be seen that the engagement of the teeth 65 and 69 must operate to retard the movement of the bevel gear-wheel 64, thus providing for a 90 relatively slow motion of the corresponding valve-stem during the travel of the point of the cam-frame between the points 70^c and 70^a. In the manner hereinafter described the casings 70 are so set as to result when said cam-point is between the points 70^a and 70^b in the 95 opening of the corresponding valve 28 or the bringing of the slotted opening 31 of said valve into communication with the interior of the corresponding combustion-chamber 100 26. This communication between said valve and combustion-chamber continues until the point of the cam-frame 68 is again at the point 70^c; but it is obvious that when the cam-frame point reaches the point 70^b of the 105 bearing-surface said cam-point will move or jump to the point 70^c with a comparatively quick motion, which is accelerated by the tension of the spring 63, thus providing for a rapid closing movement of the valve. It will 110 be understood that the time of the closing of the valves must depend upon the positions of the casings 70 and that by moving the lever extension of one of the arms 84^a either forward or backward the point 70^b may be 115 changed with reference to its location or direction from the shaft, so as to bring the point of the cam-frame at said closing-point 70^b at an earlier or later time. It will also 120 be understood that the opening of the valves will occur at the same point in relation to the power-piston irrespective of the positions of casings 70, due to the arc of circle 70^a to 70^c.

I have heretofore described the outward movement of one of the pistons and the 125 means by which the same is driven, and it will readily be seen that the pistons of the three power-cylinders herein shown will be similarly operated in succession. As each of the power-cylinder pistons nears its outer 130 limit the projecting portion of the corresponding cam 62 on the shaft 61 comes into such contact with the outer end of the corresponding lever 82 as to raise the outer end of

said lever and depress the inner end thereof, thereby opening the valve 86, with which said lever 82 is in contact, and permitting the products of combustion to escape through 5 the exhaust-pipe 77.

By the motion imparted to the crank-shaft in the manner hereinbefore described it is obvious that a reciprocating motion will be imparted to the piston 14 of the air-compressor cylinder. In the movement of this latter piston toward the end of its cylinder the valve 46 will be drawn open and the supply of air admitted, and on the return movement of said piston it is obvious that said 10 valve 46 will be closed and that the valve 40 will be forced open, thereby permitting the air to be driven under pressure into the pipe 42. Through the medium of the pipe 71 the air-reservoir 72 will be provided at all times 15 with a supply of air under pressure. It will be understood that the gasolene-tank 25 will be supplied with air under pressure through the medium of the pipe 24^a, the compression of the air therefore being attained through 20 the reciprocating motion of the air-pump piston 17 imparted from the crank-shaft. In order to insure a proper discharge of gasolene against the air in the valves 28, it is desired that the pressure within the gasolene- 25 tank be greater than the pressure within the pipe 42, and it is for this reason that I employ the heretofore-described regulating device which is shown in detail in Fig. 15 of the drawings and the operation of which is 30 as follows: The central diaphragm 90 has its opening normally closed by contact with the tapering end of the screw 92; but when the air-pressure within the casing formed by the plates 89 on the right side of the diaphragm 35 90 becomes sufficiently great to overcome both the pressure of air on the opposite side of said diaphragm and the pressure of the spring 94 it is obvious that the diaphragm will be moved sufficiently to permit the air from 40 the high-pressure side thereof to flow to the comparatively low-pressure side; but owing to the employment of the spring 94 it is obvious that a higher pressure will be normally maintained on the gasolene than within the pipe 45 42 and the valve. In case the air-compressor piston 14 is working against a surplus of air-pressure in the pipe 42 or a greater pressure than is desired for properly supplying the combustion-chambers it will be understood 50 that this increased pressure will exert such depressing influence on the diaphragm 53 of the casing 51 as to produce a downward movement of the arm 55^a and outward movement of the arm 55^b of the bell-crank lever 55, this 55 movement of said bell-crank placing the spring 58 under tension. The outward movement of the arm 55^b of the lever results in permitting the latch or binding-plate 49 to drop outward until it intersects the valve-stem 46^a 60 on an incline, and causes said valve-stem to bind therein on its outward stroke, thus preventing the closing of the valve 46 and per-

mitting the escape of air therethrough on the inner movement of the piston 14 of the air-compressor. When the pressure in the pipe 70 42 is sufficiently relieved to permit the spring 58 to perform its office of moving the lever-arm 55^b inward, it is obvious that the binding-plate 49 will be returned to its normal position, and that the valve 46 will again be 75 free to close.

Having now fully described my invention, what I claim, and desire to secure by Letters Patent, is—

1. In an internal-combustion engine, the 80 combination with a plurality of power-cylinders, each of said power-cylinders having an exhaust - outlet and combustion - chamber communicating therewith, a crank-shaft, pistons in said cylinders connected with the 85 cranks of said shaft, of hollow rotary valves adapted to communicate at each revolution with the interiors of the combustion-chambers, a rotary shaft operating said hollow valves, cams on said shaft, exhaust-valves 90 for the power-cylinders, fulcrumed exhaust-valve - operating levers having their outer ends adapted to contact with said shaft-cams and their rear ends adapted to impart opening movements to said exhaust-valves, means 95 for supplying air and gasolene under pressure to said hollow valves and means for igniting the combined gasolene and air within said combustion-chambers, substantially as specified. 100

2. In an internal-combustion engine, the 105 combination with a plurality of power-cylinders, pistons working therein, a crank-shaft to which said pistons are connected, and combustion-chambers communicating with said cylinders, of hollow rotary valves adapted to communicate at each revolution with said combustion-chambers, a rotary shaft 61 operated from said crank-shaft, connections between said shaft 61 and the stems of said rotary valve whereby a variation in the speed 110 of said rotary valves is attained which will insure a comparatively rapid closing of the valves, means for supplying air and gasolene under pressure to said combustion-chambers 115 and for igniting the same within the combustion-chambers, substantially as specified. 120

3. In an internal-combustion engine, the 125 combination with a plurality of power-cylinders, pistons working therein, a crank-shaft to which said pistons are connected, and combustion - chambers communicating with said cylinders, of rotatably-mounted hollow valves adapted to communicate at each revolution with said combustion-chambers, a rotary shaft 61 operated from the crank-shaft, bodies 62, arms 66 carried by said shaft, gear-wheels 64 loose on the shaft 61, springs connecting said gear-wheels with said bodies 62, a cam-frame 68 connected at one side with 130 each of the arms 66, a casing 70 loose on the shaft 61 about each of said cam-frames, a cam-frame bearing-surface within said casing comprising as described a spiral curve, a curve

6 having the arc of a circle and an outward curve connecting said circle-arc with the point of beginning of the spiral curve, said cam-frame having a plurality of teeth on its longer 5 arm adapted to gear with teeth on an extension of the gear-wheel 64, gear connections between said wheels 64 and the stems of said rotary valves, means for rocking the casings 70 on the shaft 61, means for supplying air and 10 gas to the combustion-chambers and means for igniting the combined air and gas within the combustion-chambers of the power-cylinders, substantially as specified.

4. In an internal-combustion engine, the 15 combination with a plurality of power-cylinders, pistons working therein, a crank-shaft with which said pistons are connected, combustion-chambers communicating with each of said power-cylinders, an air-compressor 20 cylinder 15, a piston therein, said piston connected with said crank-shaft, a gasolene-tank, an air-reservoir, an air-pump cylinder 18 having inlet and outlet valve-controlled openings, a piston in said air-pump cylinder, said 25 piston connected with said crank-shaft, and a pipe connection between the outlet of said air-pump cylinder and said gasolene-tank, of rotary hollow valves adapted to communicate at each revolution with the piston-chambers 30 of the power-cylinders, a pipe 42 leading from

the air-compressor cylinder 15 and distributing air to said rotary valve, a gasolene-conducting pipe leading from the gasolene-tank to and communicating with said rotary valves, substantially as specified.

5. In an internal-combustion engine, the combination with a power-cylinder, a reciprocating piston therein, a combustion-chamber communicating with said power-cylinder, and an air-conducting pipe conveying air to 40 said combustion-chamber, of a gasolene-tank, a gasolene-conducting pipe through which gasolene is conducted to said combustion-chamber, an air-compressor, a pipe connection 45 between said air-compressor and said gasolene-tank, a pipe 75 leading from said pipe 24^a to the air-supply pipe for the combustion-chamber, a casing intersecting said pipe 75 and with opposite sides of which separated sections of said pipe connect, a central dia- 50 phragm in said casing having a central opening, a valve on the rear side of said dia- phragm and normally closing the opening therein, and a spring exerting a rearward pressure on the forward side of said diaphragm, 55 substantially as specified.

WILLIAM M. BRITTON.
